Primary Examiner — Clare E Heflin(74) *Attorney, Agent, or Firm* — Tsircou Law, PC(57) **CLAIM**

We claim the ornamental design for a light fixture, as shown and described.

DESCRIPTION

FIG. 1 a front perspective view of a light fixture of the new design.

FIG. 2 is a front elevational view of the light fixture of FIG. 1.

FIG. 3 is a back perspective view of the light fixture of FIG. 1.

FIG. 4 is a back elevational view of the light fixture of FIG. 1.

FIG. 5 is a side view of the light fixture of FIG. 1, which is a mirror image of the opposite side; and,

FIG. 6 is top view of the light fixture of FIG. 1, which is a mirror image of the bottom view.

The dashed lines depict environmental aspects and form no part of the claimed design.

1 Claim, 5 Drawing Sheets
